(57) **CLAIM**

The ornamental design for an air purifier with light as shown and described.

DESCRIPTION

The patent or application file contains at least one drawing executed in color. Copies of this patent or patent application publication with color drawings will be provided by the Office upon request and payment of the necessary fee.

FIG. 1 is a perspective view of an air purifier with light showing our new design;

FIG. 2 is a front elevation view thereof, a rear elevation view being a mirror image thereof;

FIG. 3 is a left-side elevation view thereof, a right-side elevation view being a mirror image thereof;

FIG. 4 is a top plan view thereof;

FIG. 5 is a bottom plan view thereof; and,

FIG. 6 is an exploded perspective view of an air purifier with light in an alternate configuration with the colored portions of the air purifier with light showing the lighting turned on.
